US00D790497S

(12) **United States Design Patent** (10) **Patent No.:** **US D790,497 S**
(45) **Date of Patent:** **** Jun. 27, 2017**

(54) **ELECTRONIC DEVICE**

(71) Applicant: **Samsung Electronics Co., Ltd.**, Suwon-si (KR)

(72) Inventors: **Sung-Kwon Kim**, Seoul (KR); **Sang-Min Hyun**, Seoul (KR); **Kwan-Eui Hong**, Yongin-si (KR)

(73) Assignee: **SAMSUNG ELECTRONICS CO., LTD.**, Suwon-si (KR)

(**) Term: **15 Years**

(21) Appl. No.: **29/528,110**

(22) Filed: **May 26, 2015**

(30) **Foreign Application Priority Data**

Dec. 1, 2014 (KR) 30-2014-0058128

(51) **LOC (10) Cl.** **14-03**

(52) **U.S. Cl.**

USPC ..... **D14/138 AA**

(58) **Field of Classification Search**

USPC ..... D13/168; D14/138 G, 138 R, 138 AD, D14/203.1, 203.3, 203.5, 203.6, 203.7, D14/218, 248, 250, 315, 341, 342, 343, D14/344, 345, 346, 347, 420, 426, 496

CPC G06F 1/1626; H04M 1/72527; H04M 1/0266; H04M 1/185; H04M 1/0214

(57) **CLAIM**

The ornamental design for an electronic device, as shown and described.

DESCRIPTION

FIG. 1 is a top right front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dashed broken lines in the drawings represent portions of the electronic device that form no part of the claimed design.

1 Claim, 5 Drawing Sheets
